United States Patent Office.

CHARLES BROWN, OF CHARLOTTESVILLE, VIRGINIA.

Letters Patent No. 99,517, dated February 1, 1870.

IMPROVED BOOT-JACK.

The Schedule referred to in these Letters Patent and making part of the same.

To all whom it may concern:

Be it known that I, CHARLES BROWN, of Charlottesville, Albemarle county, in the State of Virginia, have invented certain Improvements in "Boot-Jacks," of which the following is a specification.

The nature of my invention consists in constructing a cheap and portable boot-jack, of which the following is a description.

In the drawings—

Figure 1 is a perspective view of my improved boot-jack, and

Figure 2 shows it in position, or applied to a boot for operation.

A represents a continuous leather strap, about an inch in width, and the thickness of heavy upper or light strap-leather. In length, it is usually eighteen to twenty-four inches, more or less.

a is a slit cut in the length of the strap, sufficiently long to slip the foot through, as represented in fig. 2,

which shows half, C, of the strap where it is divided over the instep, and the other half, D, behind the heel, whilst the rest passes down around and under the foot.

A pull on the part B, by the other foot, readily removes the boot.

The strap can be easily carried in the pocket or in a valise or trunk.

Having described my invention,

What I claim as new, and desire to secure by Letters Patent of the United States, is—

As a new article of manufacture, a portable boot-jack, made of a leather strap or other equivalent material, and provided with a slit, a, cut lengthwise of the strap, as herein shown and described.

CHARLES BROWN.
